UNITED STATES PATENT OFFICE.

WILLIAM J. DE WITT, OF AUBURN, NEW YORK.

HEEL FOR FOOTWEAR AND METHOD OF ATTACHING THE SAME.

Application filed April 24, 1926. Serial No. 104,366.

This invention pertains to the manufacture of footwear and more particularly to heels for boots, shoes, etc., and to a method of attaching such heels. Various substitutes for heels built up of lifts of leather, fibre board, etc., have been proposed, the most common of such substitutes being the wood heel modeled from a solid block of hard wood. While the wood heel is relatively cheap and quite strong and durable, it presents several serious problems to the shoe manufacturer, one being the difficulty of finishing the exterior surfaces of such a wooden block to give it the appearance of leather, and a second and even more important being the difficulty of attaching the wood heel securely to the shoe.

This latter difficulty arises from the fact that it is not practical to attach the heels by means of nails driven from the tread surface of the heel and clenched against the inner surface of the shoe sole, which is the method of attaching leather heels, since the wood heel will split when so treated. It has, therefore, been common to attach such wood heels by means of wood screws or short nails driven from the inside of the shoe sole into the heel, but the difficulty of setting wood screws as compared with driving nails is considerable, while there is no way of clenching nails driven downwardly through the shoe sole into the heel, and therefore such nails provide a very unreliable fastening and in consequence wood heels frequently become detached from the shoe.

In accordance with the present invention I provide a heel which may be made at a cost not substantially greater than that of solid wooden heels, which may without difficulty be given a permanent external finish closely resembling that of highly polished leather, and which can be attached by means of clenched nails or other equivalents in an expeditious manner and by the use of apparatus of substantially the usual type.

Other advantages of the invention will be apparent as the description proceeds and will be particularly pointed out in the appended claims.

In the drawings,

Fig. 1 is a fragmentary elevation of the rear part of a shoe showing the improved heel attached thereto and with an anvil member in place for clenching the attaching nails;

Fig. 2 is a longitudinal vertical section

through the improved heel showing the closure plate removed;

Fig. 3 is an elevation of the heel looking toward the breast surface thereof, the cover plate being removed; and

Fig. 4 is a section similar to Fig. 2 but illustrating a modified type of heel and a different type of fastener.

Referring to the drawings the numeral 1 designates the improved heel which may be given any desired external shape in accordance with the style of shoe to which it is to be attached. The present heels differ from heels of prior construction in having an interior cavity 2 of any suitable contour and size, such cavity being here shown as substantially rectangular and having an upper wall 3 and a lower wall 4. Preferably the inner surface 5 of the upper wall 3 is substantially flat and parallel with the outer surface 4, but this is not essential.

The heel thus formed may be made by a molding or pressing operation from any substance having suitable characteristics, for example, celluloid, hard rubber, paper or fibre pulp, etc., or may be shaped from wood, sheet metal, or in fact almost any material by an appropriate process.

The cavity 2 preferably opens at the breast surface of the heel and the edge of the opening is preferably rabbeted at 6 to provide a recess for the reception of the edge of a cover plate 7 which may be of the same or a different material from the body portion of the heel. After the heel has been attached to the shoe as hereafter described this cover is secured in position by the use of adhesive or otherwise and as it seats within the rabbet a flush and finished surface is produced.

The upper surface 9 of the heel is shaped as usual to fit snugly against the under surface of the heel seat portion of the shoe sole 10. In attaching the heel to the shoe an anvil member 11, which may conveniently be attached to the frame 12 of a nailing machine, for example of any usual type employed for attaching wood heels, is introduced into the cavity 2 through the opening in the breast surface. This anvil has a substantially flat lower face upon which the surface 5 of the wall 3 of the heel may rest. Obviously if this surface 5 be other than flat and horizontal the anvil surface may correspondingly be varied.

While the heel rests upon the anvil, nails

13 are driven upwardly through the shoe sole and through the wall 3 of the heel and their points are clenched as indicated at 14 against the surface of the anvil 11. The 5 heel is thus securely attached to the shoe sole by the use of relatively short nails and is thus anchored more firmly to the shoe sole than is the ordinary leather heel. Padded buffer members 12^a and 12^b bear against the 10 outer lift 16 and rear portion of the heel respectively. These buffers are suitably movably attached to the nailing machine. While a nailing machine has been mentioned as useful in driving these nails, it is obvious 15 that they might be driven by hand if desired, in which case the anvil 11 may be supported upon a bench or in any other desired manner.

After the nails 13 have been driven, the 20 heel is withdrawn from off of the anvil and the cover plate 7 is set into the recess in the breast surface of the heel, or it may be attached in any other suitable way as by a bevelled portion instead of a recess. The 25 edges of the cover plate may be moistened with adhesive, or, if the body of the heel and the cover plate are of celluloid, which is regarded as a desirable material, the engaging surfaces of these parts may be moistened 30 with a celluloid solvent, for example acetone, which produces an integral union between them when they are pressed together.

If as suggested the heel be made of celluloid, this celluloid may be colored to resemble 35 leather of the desired shade, and since the outer surface of the heel may be given a high polish in the molding operation or by a subsequent application of acetone or a similar solvent, no difficulty is experienced 40 in giving this heel an appearance resembling polished leather and having the further advantage that this finish is quite permanent.

The heel thus formed is light in weight, 45 quite as durable as leather so far as resistance to abrasive wear is concerned, does not split readily, and remains firmly attached to the shoe sole under all conditions. If desired a top lift 15 of leather, rubber or the like may be secured to the lower wall 4 of the heel proper by means of any suitable 50 fasteners, for example the slugs 16.

In Fig. 4 a modified heel is illustrated, such heel 1^a being made, for example, of metal and having holes in its upper wall 3^a 55 for the reception of rivets 15. These rivets are passed down through the shoe sole 10^a and headed over against the inner surface 5^b of the wall 3^a by the use of an anvil inserted into the cavity 2^a of the heel body. While

this fastening means is particularly suited to a metal heel, it is, of course, applicable to heels of other materials.

If the heel proper be of a material, for example metal, which does not give the desired external finish, it may be covered as 65 indicated at 17 with any desired material, for example leather, paper, celluloid, cloth or the like, attached in the same way as such covering material is applied to wood heels. Likewise this heel may be provided 70 with a top lift 18 if desired.

While as here shown I prefer to arrange the opening leading into the cavity 2 at the breast surface of the heel, I do not wish to be limited to this arrangement since such 75 opening might perhaps be formed at some other point in the wall of the cavity.

I claim:

1. That method of attaching heels to shoes which comprises as steps forming a large 30 cavity in the heel, such cavity opening at the breast surface of the heel, fastening the heel to the shoe with fastening members extending from the inside of the shoe through the sole and upper wall of the 35 cavity, clenching the fastening means against the inner surface of said wall, and thereafter closing the entrance to the cavity.

2. A heel for shoes having a cavity for the 40 reception of an anvil upon which heel attached fasteners may be clenched, said cavity opening at the breast surface of the heel, and a plate for covering the entrance to said cavity.

3. A shoe heel of molded celluloid having 45 an interior cavity opening at its breast surface and a cover member of celluloid for closing the aperture leading to said cavity, said cover member being connected to the heel body by forming an adhesive surface 100 therebetween.

4. A shoe heel consisting of a hollow shell having an aperture in its breast wall for the insertion of an anvil, a cover for said aperture, and means covering the outer surface 105 of the heel proper to provide a finish therefor.

5. A shoe heel consisting of a hollow celluloid shell having an aperture through its breast wall, the edge of the aperture being 110 rabbeted to provide a marginal recess, and a celluloid cover normally having its edge seated in said recess to close said aperture, said cover being attached in place by forming an adhering surface with said edge.

Signed by me at Auburn, New York, this 115 15th day of April, 1926.

WILLIAM J. DE WITT.
